[57] CLAIM

The ornamental design for a combined flashlight and
fluorescent lantern, as shown and described.

DESCRIPTION

FIG. 1 is a perspective view of a combined flashlight and
fluorescent lantern showing my new design;
FIG. 2 is a top plan view thereof, on an enlarged scale;
FIG. 3 is a right side elevational view thereof, on an
enlarged scale, the left side being a mirror image;
FIG. 4 is a bottom plan view thereof, on an enlarged
scale;
FIG. 5 is a front elevational view thereof, on an en-
larged scale;
FIG. 6 is a rear elevational view thereof, on an enlarged
scale.

FIG. 1

FIG. 2

FIG. 3
